Primary Examiner — Susan Moon Lee

CLAIM

I claim the ornamental design for a top paw fountain, as shown and described.

DESCRIPTION

FIG. 1 is a perspective view of a top paw fountain, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The appearance of the underside of the fountain is not claimed.
